DOME COVER FOR TANK CARS

George W. King, Coffeyville, Kans., assignor of two-twelfths to Lee T. Englund, two-twelfths to John E. Mahan, both of Coffeyville, Kans., and seven-twelfths to Roy T. Osborn, New York, N. Y.

Application November 27, 1931, Serial No. 577,488

3 Claims. (Cl. 220—24)

My invention relates to dome covers for tank cars and is primarily concerned with providing a cover that may be readily interchanged with present types of threaded dome covers without requiring any modifications of existing structures.

One object of my invention is to devise a dome cover which may be readily substituted for the threaded cover now in standard use and which will provide a cover structure having sealing characteristics sufficiently adequate to meet the requirements of a casing head gasoline tank car dome cover.

A further object is to provide a dome cover which permits the utilization of the present dome ring and which enables the cover proper to be secured in position by attachment other than screw threads, so that the cover will provide a more effective seal against vapor pressure.

20 A further object is to provide a cover of the character indicated which is held in position by a series of swingably mounted bolts which are permanently attached to a collar fixed to the dome of the tank car, the position of the bolts when the cover is in securing position being such that, when the bolts are being loosened to permit removal of the cover, a sufficient retaining engagement of the bolts with the cover is maintained while the cover is capacitated for a slight movement away from the valve seat to relieve any excessive pressure within the tank car.

A large number of the tank cars now in operation are provided with the old screw type of dome cover which, through continued use, becomes so battered and worn as to be very objectionable, particularly where the car is being employed for the transportation of volatile, inflammable vapors and liquids. The screw type of dome cover is intended to form a sealing engagement with the dome ring through the medium of a lead packing ring, but this ring, over a period of time, becomes dented and will not satisfactorily operate as a sealing element. The latter condition obtains particularly when the car is being coupled in train, causing a spraying of the contents outwardly on the surface of the car between the cover and dome ring. The threads on these types of covers also become worn with the result that the cover eventually reaches a condition of the so-called drop lid, necessitating an actual prying of the cover out of the ring by a bar or other suitable tool. The latter action obviously is very detrimental to the soft lead sealing ring. The screw cover, moreover, frequently exhibits a tendency to stick and in the

effort to loosen the cover, it is very often cracked and there is always the danger of creating a spark during such removal with obvious results, where the car is loaded with inflammable material.

The present invention is intended to overcome the foregoing objections through providing a dome cover which may be readily mounted on those cars which are now provided with the screw type of cover. The nature of the proposed arrangement is such that the degree of sealing engagement obtainable, if the other parts of the car are in a proper condition, will satisfactorily meet the requirements established by the American Railway Association for Class IV tank cars. The new cover possesses inherent features in that, during the process of removing the cover, any excessive pressure obtaining within the tank car will be relieved prior to a complete removal of the cover.

These and further objects of my invention will be set forth in the following specification, reference being had to the accompanying drawing, and the novel means by which said objects are effectuated will be definitely pointed out in the claims.

In the drawing:

Figure 1 is a plan view of my improved cover, showing the same in relation to a portion of a tank car dome.

Fig. 2 is a section along the line 2—2 in Fig. 1, looking in the direction of the arrows.

Fig. 3 is a section along the line 3—3 in Fig. 2, looking in the direction of the arrows, and showing the manner of hingedly connecting the cover to the accompanying structure.

Referring to Fig. 2, the numeral 10 designates a portion of a tank car dome which is provided with the usual dome ring 11 that is internally threaded as at 12. A collar 13 which is exteriorly threaded adjacent its lower end is screwed into the ring 11 and the opposite end of said collar is provided with a beveled valve seat 14. Intermediate its ends, the collar 13 is provided with an annular, exteriorly positioned flange 15, between which and the ring 11 is interposed a sealing ring 16, thus providing a vapor-tight joint in the indicated location when the collar 13 is in position.

Above the flange 15, the collar 13 is provided with a plurality of lugs 17 which are preferably arranged in spaced pairs around the periphery of this collar. Bridged between each pair of said lugs is a pin 18 upon which is pivotally mounted the apertured end of an eye-bolt 19.

Accordingly, these eye-bolts are permanently and swingably mounted on the collar 13. The threaded stem of each eye-bolt 19 is intended to pass between a pair of lugs 20 which are provided on a dome cover 21, it being understood that there are as many pairs of lugs 20 as there are eye-bolts 19. The underside of the cover 21 is further provided with a preferably circular shoulder 22 having a curved cross-section which is intended to cooperate with the valve seat 14. When the cover is in the sealing position shown in Fig. 2, the bolts 19 are swung upwardly to pass between the indicated pairs of lugs 20; whereupon the nuts 23 on said bolts may be tightened to securely hold said cover in sealing position.

As an improvement on the present method of holding a screw type of dome cover with a chain, it is contemplated that the dome cover 21 will be hingedly connected to the collar 13. To this end, a hinge part 24 is provided on said collar and is shaped to extend upwardly and outwardly therefrom. A quadrant shaped slot 25 is formed in the hinge 24 to receive a hinge pin 26 that is mounted in the cover 21. It will be observed that the shape of the slot 25 is such that the cover 21 is moved upwardly and then outwardly, away from the entrance to the dome 10, while still maintaining an adequate and fixed connection to the collar 13.

In applying the dome cover above described to a tank car which has theretofore been provided with the ordinary screw type of cover, it is only necessary to remove the latter and to replace, where necessary, a new sealing ring for the ring denoted by the numeral 16. Thereafter, the collar 13 is threaded in the dome ring 11 and the cover 21 may be bolted in position as above described.

The nature of the cooperating valve parts of the cover and collar is such that a very effective seal is provided against vapor pressure, with the further advantage that such valve parts are not easily damaged in use. The collar 13, with its associated eye-bolts, remains permanently in position on the car, leaving only the dome cover 21 to be loosened and swung outwardly on its hinge 24. During such loosening movement, it will be obvious that the initial unscrewing movement of the nuts 23 will permit a sufficient axial movement of the cover to relieve any excess vapor pressure that may obtain within the tank and

that during this relief, the cover 21 will still be adequately held against any sudden movement outwardly by the bolts 19. The improved cover may be readily substituted for existing threaded covers without requiring any changes in the remaining portion of the dome structure.

While I have shown one set of elements and combinations thereof for effectuating my improved dome cover, it will be understood that the same is intended for illustration only and in no wise to restrict the device to the exact forms and structures shown, for many changes may be made therein without departing from the spirit of my invention, such as the adaptation of the dome cover to tanks in general. The application of the improved dome cover to tank cars has been adopted for purpose of description only and is not to be considered as restrictive in nature, although the dome cover does have specific advantages in respect of a tank car.

I claim:

1. In a tank car, the combination of an internally threaded dome ring intended to normally receive a threaded dome cover, a collar threaded in said ring and having a valve seat, said collar having sealing contact with said ring, bolt means mounted on said collar, a cover having a part for sealably cooperating with said seat, and parts on said cover cooperating with said bolt means for holding the cover in position.

2. In a tank car, the combination of an internally threaded dome ring intended to normally receive a threaded dome cover, a collar threaded in said ring and having a valve seat, said collar having sealing contact with said ring, a plurality of securing bolts swingably mounted on said collar, a cover having a part for sealably cooperating with said seat, and spaced lugs on said cover operating in conjunction with said bolts and nuts on said bolts for holding the cover in position.

3. In a tank car, the combination of an internally threaded dome ring intended to normally receive a threaded dome cover, a collar having a valve seat threaded in said ring and being provided with an annular flange overlying said ring for sealing contact therewith, a cover having a part for sealably cooperating with said seat, ears extending outwardly from said collar above said flange, and bolt means mounted on said ears and engaging said cover to hold the same in position.

GEORGE W. KING.
